UNITED STATES PATENT OFFICE.

JOHN W. SMITH, OF CHICAGO, ILLINOIS.

SOUND-DEADENING CASING FOR VACUUM-CLEANERS.

1,030,933.

Specification of Letters Patent.

Patented July 2, 1912.

Application filed May 18, 1909. Serial No. 496,756.

To all whom it may concern:

Be it known that I, JOHN W. SMITH, a citizen of the United States, residing at Chicago, in the county of Cook, State of Illinois, have invented a new and useful Sound-Deadening Casing for Vacuum-Cleaners, of which the following is a specification.

In the devices heretofore employed for vacuum cleaning apparatus wherein a pumping mechanism is operated by a suitable motor and the articles are cleaned by passing thereover or in proximity thereto a suction nozzle which is connected by means of a suitable hose with the pumping mechanism, it has been deemed necessary to either employ a large casing in order that a pumping mechanism having a long stroke could be employed or it has been deemed necessary to construct the pumping mechanism of such size that a motor of corresponding size must be employed, the size and weight of which is so great that the vacuum cleaning device is not readily trans-
portable but must be supported on some kind of a truck. This condition has arisen owing to the fact that it has heretofore been found impracticable to employ a standard motor which runs at a high speed since the valves heretofore employed in devices of this character would not act rapidly enough. In order to overcome these defects and produce a cleaning mechanism of maximum power and minimum weight, I have devised a novel construction of a pumping apparatus for portable vacuum cleaners wherein the pumping mechanism may be actuated at a very high speed, the same being driven in practice between fifteen hundred and four thousand revolutions per minute, and when running at such a high speed it is essential in a portable device which is employed in houses to employ some means to reduce the noise caused by the pulsation of the air, the running of the motor and the exhaust of air from the pump casing, and in my present construction I have designed a novel construction of a pump casing by the employment of which the vacuum cleaning device is practically noiseless at high speeds.

To the above ends my present invention consists of a novel construction of a pump casing for vacuum cleaners wherein means are provided for reducing to a minimum the noise caused by the operation of the device.

It further consists of a novel construction

of a pump casing comprising a plurality of shells having sound-deadening material therebetween.

It further consists of a novel construction of a pump casing wherein the sides of the same comprise a plurality of shells having sound-deadening material and an air space therebetween, the bottom of said device being provided with a desired number of layers of sound-deadening material on which the motor or the contacts therefor are adapted to be supported, said casing having a cover removably secured thereto and in air tight engagement therewith, and means also being provided for supporting the pumping apparatus and the motor within the casing.

It further consists of novel means for supporting the motor, novel means of mounting the lead terminals so that when the pump unit is placed in the casing the motor carried thereby will be in suitable engagement with the lead terminals, and novel means of mounting the motor controlling mechanism.

It further consists of a novel manner of correlating and arranging a sound-deadening casing so that the exhaust port leading from the casing is provided with a muffler mechanism preferably located within the casing.

It further consists of a novel construction of a pump cover which is formed in such a manner that the condition of the fluid entering the pump casing may be readily observed by the operator, said cover being also provided with a novel construction of handle.

It further consists of a novel manner of forming an air tight joint between the cover and the casing.

It further consists of other novel features of construction all as will be hereinafter fully set forth.

For the purpose of illustrating my invention I have shown in the accompanying drawings a preferred construction many thousands of which are now in use, the same conforming to a co-pending application for pneumatic pumping apparatus filed by me on even date with the present application, the broad principle involved being the same as that shown in my application for portable pneumatic pumping apparatus, filed May 29th, 1908, Serial No. 435,633 and patented May 11th, 1909, and this embodiment has

been found in practice to give very satisfactory and reliable results, but it is of course to be understood that the various instrumentalities of which my invention consists can be variously arranged and organized and that my invention is not limited to the exact arrangement and organization of these instrumentalities as herein set forth.

Figure 1 represents a sectional elevation 10 of a pump casing for vacuum cleaners embodying my invention. Fig. 2 represents a sectional elevation of a portion of Fig. 1 showing certain details as seen in Fig. 3. Fig. 3 represents a sectional elevation on an 15 enlarged scale of a portion of my device showing more clearly the construction of the upper portion of the casing. Fig. 4 represents a sectional elevation on an enlarged scale of a portion of my device showing more 20 clearly the construction of the bottom of the device. Fig. 5 represents a sectional view showing more clearly certain details 25 in the construction of the casing cover.

Similar numerals of reference indicate 25 corresponding parts in the figures.

Referring to the drawings:—In the detailed description of the device shown I have deemed it unnecessary to describe in detail either the pump mechanism or the 30 filter mechanism since the same are described and broadly claimed in two co-pending applications to which reference may be had for a detailed description of the construction and operation of such devices.

35 1 designates a base or bottom member to which the rollers 2 are secured in any suitable manner, said rollers being preferably provided with ball bearings 3, the purpose of which is evident.

40 4 designates the outer shell or casing, the lower end of which is deflected as indicated at 5 around the base 1 and the upper end of the shell 4 is outwardly deflected as indicated at 6, as best seen in Fig. 3.

45 7 designates an intermediate shell, the lower end of which is deflected outwardly as indicated at 8, the upper end of said shell being also deflected outwardly as indicated at 9.

50 10 designates a shell intermediate the shell 7 and the inner shell 13.

14 and 15 designate layers of sound-deadening material such as for example felt, and 55 16 designates an air space. The lower end of the inner shell 13 is inwardly deflected at 17 while its upper end is inwardly deflected to form an annular groove 18, it being noted that the inwardly deflected portion engages the shell 10 and the upper portion of the 60 inner shell 13 is inwardly deflected as indicated at 19 in order that the same may engage with the inner wall of the shell 10.

20 20 designates a plate or locking member, the outer periphery of which is deflected 65 under the extension 6 of the outer shell 4

while the inner periphery of said member 20 is deflected downwardly into engagement with the deflected portion 19 of the inner shell 13, thereby locking the upper part of the casing members in assembled position. 70

21 designates a plate, the outer periphery of which is upwardly deflected into engagement with the outer shell 4 and then deflected into engagement with the extension 8 of the shell 7. Above the plate 21 is placed 75 a layer of sound-deadening material 22, then a plate 23, then a layer of sound-deadening material 24, and above the latter is placed a plate 25 on which, in the present instance, the lower end of the shells 7 and 12 are 80 seated.

Above the plate 25 is placed a layer of sound-deadening material 26 and above the latter is placed a plate 27, the outer periphery of which is deflected downwardly and laterally as indicated at 28 and then upwardly and inwardly as indicated at 29 into engagement with the extension 17 of the inner shell 13, thereby locking said inner shell firmly in position. It will thus be 90 seen that the upper portions of the members constituting the casings are properly secured in assembled position by means of the member 20 while the lower portion of 95 said members are properly secured in position by means of the members forming the resilient base of the casing.

In order to form an air tight connection between the cover 30 and the plate 20 the ring 31 supporting the bag 32 of the filtering mechanism has its outer periphery engaged by the U-shaped gasket 33 so as to form an air tight connection when the cover is secured in position, it being noted that the outer shell 4 has secured thereto in any suitable manner a bracket 34 to which is movably connected the threaded member 35 provided with a suitable locking nut 36, said member 35 being adapted to enter the slotted extension 37 of the cover 30, whereby said 100 cover may be readily assembled with respect to the casing or disengaged therefrom. The groove 18 in the inner shell 13 is for the reception of the resilient ring 38 to which the bag 39 of the filtering mechanism is secured. 110

40 designates a pump unit which is adapted to be seated on the packing 41, the latter being supported in a groove in a support 44 which latter is integral with the inner shell 13 or secured thereto by means of suitable fastening devices 45. The pump unit 40 includes a motor 46, the shaft of which is connected by means of rods 47 with the movable member of the pump as will be 120 readily understood by reference to my co-pending application for pneumatic pumping apparatus to which I have hereinbefore referred. 125

48 and 49 designate contact members car- 130

ried by the pump unit 40 which are seated on the spring contact members 50 and 51 respectively, the two latter forming the lead terminals and being supported on the posts 52 and 53. The posts 52 and 53 are carried by a plate 54 supported on the resilient base of the pump casing. The post 53 is connected by means of a conductor 70 with a switch 55 and thence to the cable 56 to which latter the conductor 57 leads, the latter being connected to the binding post 52, it being noted that an insulating bushing 58 is provided through which the cable 56 passes. The switch 55 is secured in any suitable manner to a tube 59 which is inserted in the side of the casing, it being seen from Fig. 2 that the outer casing member 4 is deflected thereover in order to secure the same in assembled position.

20 60 designates a muffler of any unusual or conventional type the air exhausting from the pressure compartment 61 passing in the direction indicated by the arrows, to the outlet 62 which is formed by a preferably 25 tapered tube suitably secured to the pump casing in any desired manner.

The cover 30 is provided with a preferably tapered inlet port 63 through which the incoming air may pass into the vacuum 30 compartment 64 in which the filtering mechanism is located. The cover 30 in the present instance is provided with the extensions 65 to which is suitably secured a handle 66, it being noted that the handle 66 is of such 35 length that it is adapted to be grasped by the hands of two persons standing on opposite sides of the casing, if desired. The cover 30 is provided with means for observing the condition of the air entering the 40 inlet port 63 and as best seen in Fig. 5, the cover 30 is provided with a plate 67 over which the air must pass, and above the plate 67 the cover has preferably removably secured thereto a holder 68, the top of 45 which is provided with suitable transparent material 69.

The muffler 60 comprises a casing 71 which is preferably supported within the pressure reservoir 61 in such a manner as to completely inclose the inner end of the exhaust port 62. The casing 71 is provided with an inlet port 72 which communicates with a chamber 73, which latter communicates by means of a port 74 with a chamber 75, 55 having a port 76 which communicates with a chamber 77. This chamber 77 communicates by a port 78 with the chamber 79, it being seen that the casing 80 of the muffler mechanism is located within 60 in the casing 71 in such a manner that the air passing from the port 78 will have an indirect path to the exhaust port 62. It will be seen that the ports 72, 74, 76 and 78 are arranged in staggered relation with respect 65 to each other.

I have deemed it unnecessary to describe, in detail, the complete operation of the vacuum cleaning device, since it will be apparent that when the switch 55 is actuated, current may pass to the motor 46 and actuate the latter. The pumping mechanism will then be operated so that dust laden air will be drawn in through port 63 passing over the plate 67 in such a manner that the condition of the incoming air may be observed 75 through the transparent member 69, the air then passing into the vacuum reservoir 64, wherein is located the filtering mechanism which removes from the air the impurities contained therein, the air then passing 80 through the pumping mechanism into the pressure compartment 61 and thence through the muffler to the exhaust port 62 and to the atmosphere.

It will of course be apparent that the different parts of the casing and the sound-deadening material located therein may be arranged in any suitable manner and in the present instance, I have described in detail but one manner in which the parts may be 90 arranged and assembled with respect to each other. It will be further apparent that while for the purpose of illustration, I have shown the sound-deadening casing as having the cover removably secured thereto and the 95 bottom integral therewith, that if desired the bottom of the casing may also be removably secured to the sides of the casing in any suitable manner and still be within the scope of my invention. It will also be apparent 10 from Fig. 2 that in my present construction, I locate the switch which controls the motor so that the same is contained within the outer circumference of the shell so that there is no liability of the same becoming 10 accidentally operated or injured in any manner.

It will be apparent that by forming the internal bore of the inlet and outlet ports tapered the same are adapted to be connected with a suitable hose by simply pushing the metallic connection thereof into the inlet or outlet thereby dispensing with the necessity of forming screw threads or other coupling devices.

It will now be apparent that I have devised a new and useful construction of a casing especially adapted for vacuum cleaners which embodies the features of advantage enumerated as desirable in the foregoing, and while I have in the present instance shown and described a preferred embodiment thereof, which corresponds to several thousands now in practical use, it is to be understood that the same is susceptible 120 of modification in various particulars without departing from the spirit and scope of the invention or sacrificing any of its advantages.

Having thus described my invention, 130

what I claim as new and desire to secure by Letters Patent, is:—

1. As a new article of manufacture, a casing for vacuum pumps comprising a plurality of members, sound-deadening material intermediate said members, there being also an air space intermediate the inner and outer of said members, said casing having a port therethrough and having a portion thereof inwardly deflected to form a chamber, said casing having an open end, a cover, and means for removably securing said cover in air tight engagement with said end. 10
2. In a casing for vacuum cleaners, a base, sound-deadening material thereon, an inner and an outer shell supported on the base, sound-deadening material between the shells, means for closing the upper ends of the shells, said inner shell being deflected near one end to form a groove, a ring seated on said means, a U-shaped gasket, a cover engaging said gasket, fastening devices movably carried by the casing and engaging said cover, and a handle extending substantially across said cover. 20
3. In a casing for vacuum cleaners, a base, sound-deadening material thereon, a plurality of shells carried by said base, sound-deadening material between said shells, said shells having a port therethrough, an opening for reception of a conductor and provided with an inwardly deflected portion forming a switch receiving chamber, means for closing the upper ends of the shells, a cover, and means for securing the cover in air tight engagement with said means. 30
4. In a casing for vacuum cleaners, a base, sound-deadening material thereon, rollers carried by the base, a plurality of shells mounted on the base, layers of sound-deadening material and an air space between the shells, means passing through said shells for forming a switch receiving chamber, said shells having an exhaust port and an opening, a conductor in said opening and operatively connected with the switch, binding posts carried by the base and connected with the conductor, contact plates communicating with said posts, a cover, and means for securing the cover in assembled position. 40
5. In a casing for vacuum cleaners, a base, a plurality of shells thereon, sound-deadening material between the shells, said shells
- having an exhaust port therethrough, a muffling device secured within the casing and surrounding the exhaust port, a sealing member at the outer end of the shells, a cover engaging said member, and means for removably securing the cover in assembled position. 60
6. In a device of the character described, a cylindrical casing comprising a plurality of shells, layers of sound-deadening material between the shells, a base, sound-deadening material on the base, a ring, sealing means on opposite side of said ring and engaging the casing, a cover having an inlet port and seated on said means, and means for removably securing the cover in place. 65
7. In a device of the class described, the combination of a base, a vertical wall composed of a plurality of spaced shells, the space between the inmost shell and that immediately surrounding it being vacant, and a support for the machine on the vertical wall located a substantial distance from the base and constituting the only support for the machine. 75
8. In a device of the class described, a cylindrical casing, a base, a cover for the casing, a rigid ring having sealing material on opposite sides thereof interposed between the cover and the cylindrical casing. 80
9. In a device of the class described, the combination of a cylindrical casing, a cover therefor, a ring interposed between the cover and the casing having sealing material on opposite faces thereof, the ring being extended inwardly and then curved outwardly toward the wall of the casing to form a groove for the reception of the edge of a filter bag. 85
10. In a device of the class described, the combination of a cylindrical casing having an open upper end, a groove in the interior wall thereof adjacent the open upper end, a cover for the casing, and a sheet-metal ring having packing material on opposite faces thereof interposed between the casing and cover and projecting inwardly toward the center of the casing and then curved outwardly toward the wall of the casing to provide a groove for the reception of the edge of a filter bag. 90
